UNITED STATES PATENT OFFICE.

JOHN O. OATMAN, OF TULSA, OKLAHOMA.

CROSSING-GATE.

1,286,069.

Specification of Letters Patent. Patented Nov. 26, 1918.

Application filed February 16, 1918. Serial No. 217,615.

To all whom it may concern:

Be it known that I, JOHN O. OATMAN, a citizen of the United States, residing at Tulsa, in the county of Tulsa and State of 5 Oklahoma, have invented new and useful Improvements in Crossing-Gates, of which the following is a specification.

This invention relates to new and useful improvements in crossing gates and the principal object of the invention is to provide 10 means for controlling traffic at street intersections.

Another object of the invention is to provide a series of barriers with means for lowering the barriers to close one street while simultaneously raising the barriers to open 15 the cross street.

Other objects of the invention are to provide centrally located means for controlling 20 all of the barriers, adjustable means for controlling the length of the barriers, and means for easily rendering the barriers inoperative and for removing the devices from the street.

25 Another object of the invention is to provide a device of this character which is simple and durable in construction, reliable and efficient in operation and one which can be manufactured and placed upon the market at a minimum cost.

The invention also consists in certain other features of construction and in the combination and arrangement of the several parts, to be hereinafter fully described, illustrated in the accompanying drawings and 35 specifically pointed out in the appended claims.

In describing my invention in detail, reference will be had to the accompanying 40 drawings wherein like characters denote like or corresponding parts throughout the several views, and in which:—

Figure 1 is an elevation showing one of the supporting posts for a pair of the barriers or gates, one gate being in open or lowered position while the other gate is in raised position.

Fig. 2 is a view taken at right angles to Fig. 1.

50 Fig. 3 is a plan view of Fig. 1.

Fig. 4 is a plan view showing the arrangement of operating parts at the intersection of two streets.

Fig. 5 illustrates the signaling means.

Fig. 6 is a sectional view of the operating means. 55

Fig. 7 is a section on line 7—7 of Fig. 6.

In these views A represents a street which is intersected by the cross street B and the drawing illustrates my improvements used 60 for controlling the pedestrian traffic on the side-walks of these streets. It will of course be understood that the invention may be used for closing the streets proper with but little change in the construction thereof. 65

At each corner of the side-walks I locate a screw threaded socket 1, said socket being located below the level of the side-walk so as to be out of the way when the gates are removed. This socket receives the screw 70 threaded end of a post or upright 2 which carries a pair of gates, the gates being located at right angles to each other. Each gate is composed of a beam 3 pivoted to one end to the post adjacent the lower end thereof, a bar 4 having its upper end hooked and slidingly engaging an eye bolt 5 adjustably secured in the post. Said bar is pivotally secured to the central part of the beam 3 by a bolt 6 adjustably mounted in said beam 80 and the other end of said bar is pivoted to a vertical bar 7 by means of a pin 8. The bar 7 is provided with a casing 9 at its lower end which carries said pin and incloses the end of the bar 4. In this manner there are 85

no projecting ends to catch in the clothing of pedestrians when the gate is being moved. The bar 7 engages with a recess 10 formed in the end of the beam 3 and a strap 11 holds the bar in said recess while permitting 90 free movement of the parts. The end of the beam 3 is connected with the end of the beam 3' of the other gate by means of a cable 12 which passes through an eye 13 carried at the top of the post. This cable is of such a length 95 that it will hold one gate in raised position while the other gate is in lowered position.

The bar 7 is of sufficient length as to remain in engagement with the strap 11 and recess 10 when the beam 3 is in vertical position, as 100 shown in Fig. 2. When the gate is in lowered position the end of the beam engages the central part of said bar 7 as shown in Fig. 1. It will be seen from this figure that the beam 3, the cable 12 and the rods 4 and 7 form a barrier or gate of such a form as to render it difficult for a person to attempt to 105 go through or over it.

The operating means for the gates consists of a centrally located standard 14 having its lower end in engagement with a socket 15 formed in the bottom of a chamber 16 made in the street at the central part of the intersection of one street with the other, said chamber being closed by a cover 17. This cover has an opening therein through which the standard passes and 10 said standard is provided with a handle 18 by which an operator, preferably a crossing policeman, may rotate said standard. The standard has secured thereto a cable operating device 19 which is located within the 15 chamber. This device is composed of two sections 20 and 21, one located above the other and having their ends of arcuate shape. The ends of each section are curved in different directions and the curves of the 20 two sections are reversely arranged as clearly shown in Fig. 7. A pair of cables indicated at 22 are secured to each section and these cables engage the curved ends, said ends being preferably grooved to receive the cables. As shown in Fig. 7 the 25 cables are secured adjacent the inner end of each curve so that the cable passes off the high part of the curve. Conduits 23 are located under the streets and extend 30 from a point adjacent one post to a point adjacent the adjacent posts and these four conduits are each connected midway of its ends with the chamber 16 by means of the conduits 24. The four cables 22 pass from 35 the member 19 over suitable rollers 25 into conduits 24. Each cable is connected with a pair of cables 25' which pass over suitable pulleys into the conduit 23 where said cables extend in opposite directions and 40 have their ends secured to the gates so that the rotation of the member 19 will cause said cables to operate the gates. As shown in Fig. 1 the end of the cable after passing through an adjustable member 26 of curved 45 shape carried by the end of the beam 3 is removably secured to an eye 27, carried by the bolt 6, by means of a snap hook 28 secured on the end of the cable. The member 26 is provided with a plurality of holes 50 by means of which it may be adjusted to any position on the beam 3. By this means the inclination of the cable 25 in respect to the beam 3 may be changed so as to render it possible for said cable to raise the beam 55 at all times thus permitting the extent of movement of said beam to be varied. By the arrangement of the cables on the curved ends of the actuating member 19 it will be seen that the cable connected with the gate 60 being raised will have sufficient slack to prevent this cable operating against the cable connected with the gate being lowered, as said first mentioned cable will be freed from the curved end of the operating device 65 quicker than the other or lowering cable is

taken up by the corresponding end of the other section of the device.

I prefer to provide electric alarms 29, one located on each post, and located in a circuit including a battery 30 and switch 31, 70 said switch being located within easy reach of the operator of the device.

It will be seen that the device is operated by the usual crossing policeman stationed at the intersection of the streets and the 75 standard 14 may contain the usual semaphore arrangement for controlling the street traffic so that when the said semaphore is set to stop traffic along one street the gates will be lowered across the side-walks of this 80 street to prevent pedestrians from crossing the street, the vehicles on which have been given the signal to cross. For instance when the member 14 has been turned to place the semaphore in position to give the 85 vehicles on street A the right of way, the operating device 19 will operate the cables to lower the gates 3 across the edges of the curb on street A so as to prevent pedestrians from crossing said street A. At the 90 same time gates 3' will be raised to permit the pedestrians to cross street B.

It is thought from the foregoing description that the advantages and novel features of my invention will be readily apparent. 95

I desire it to be understood that I may make such changes in the construction and in the combination and arrangement of the several parts, provided that such changes fall within the scope of the appended claims. 100

What I claim is:—

1. A device of the class described comprising a supporting post, a pair of gates carried thereby, one gate extending at right angles to the other gate and each gate comprising a beam pivoted at its lower end to the post, a rod pivoted intermediate its ends to the middle of the beam, an eye on the post with which the upper end of the rod slidingly engages, a vertical rod having its 110 lower end pivotally connected with the lower end of the first mentioned rod, means on the outer end of the beam slidingly engaging said vertical rod, and eye on the upper end of the post, and a cable passing 115 through said eye and connecting the ends of the beams of the gates together.

2. A device of the class described comprising a supporting post, a pair of gates carried thereby, each gate comprising a beam pivoted at one end to said post, foldable members connected with said beam and post, means for varying the extent of movement of said beam, a cable connected with the central part of the beam, a member carried by the lower end of the beam and projecting downwardly therefrom and having an eye thereon for receiving said cable, means for adjusting said member and actuating means connected with said cable. 125 130

3. A device of the class described comprising a plurality of pairs of gates, means for connecting the members of each pair together so that when one gate is lowered 5 the other is raised, a central actuating device for said gates, said device comprising a shaft, an actuating device secured thereon and consisting of two sections, each section having ends of arcuate shape, cables secured to said sections adjacent the inner ends of 10 the curves and passing around said ends to the gates.

In testimony whereof I affix my signature.
JOHN O. OATMAN.
